UNITED STATES PATENT OFFICE.

EDWARD L. COLLIS, OF CINCINNATI, OHIO.

DESIGN FOR A PEDESTAL AND JARDINIÈRE.

No. 39,016.

Specification for Design.

Patented Jan. 14, 1908.

Application filed November 16, 1907. Serial No. 402,568. Term of patent 7 years.

To all whom it may concern:

Be it known that I, EDWARD L. COLLIS, a citizen of the United States, residing at Cincinnati, in the county of Hamilton and State of Ohio, have invented a new, original, and ornamental Design for a Pedestal and Jardinière, of which the following is a specification, reference being had to the accompanying drawing, forming a part thereof.

The figure is a side elevation of a pedestal and jardinière showing my design.

I claim:

The ornamental design for a pedestal and jardinière as shown.

EDWARD L. COLLIS.
